United States Patent Office

Des. 220,729
Patented May 11, 1971

220,729

BOAT ENGINE

William P. Kitovich, Chicopee, Mass., assignor to
K & P Products Inc., Chicopee Falls, Mass.

Filed June 30, 1969, Ser. No. 17,964

Term of patent 14 years

Int. Cl. D12—14

U.S. Cl. D71—1

FIG. 1.

FIG. 2.

FIG. 1 is a front elevational view of a boat engine embodying my new design;

FIG. 2 is an end elevational view thereof as seen from the left of FIG. 1;

FIG. 3 is a rear elevational view thereof;

FIG. 4 is an end elevational view thereof as seen from the left of FIG. 3; and

FIG. 5 is a top plan view thereof.

I claim:

The ornamental design for a boat engine, as shown.
